UNITED STATES PATENT OFFICE.

EDWIN J. EVANS AND GEORGE E. HEMPHILL, OF SALT LAKE CITY, UTAH.

PIPE WRENCH.

Application filed March 17, 1922. Serial No. 544,449.

To all whom it may concern:

Be it known that we, EDWIN J. EVANS and GEORGE E. HEMPHILL, citizens of the United States, and residents of Salt Lake City, in the county of Salt Lake and State of Utah, have invented certain new and useful Improvements in Pipe Wrenches, of which the following is a specification.

This invention relates to an improvement in pipe wrenches and has for its object to provide an improvement of this character wherein the jaws of the wrench may be quickly set to engage pipes or other work of various sizes and yet at the same time be capable of being brought into powerful gripping engagement with the pipe or work.

Another object of the invention is to provide an improved pipe wrench which is of extremely simple and durable construction, reliable and convenient in operation and easy and comparatively inexpensive to manufacture.

Other objects and advantages of the invention reside in certain novel features of the construction, combination and arrangement of parts as will be hereinafter more fully described and particularly pointed out in the appended claims, reference being had to the accompanying drawings, forming a part of this specification, in which,

Figure 1 is a view in side elevation illustrating a pipe wrench embodying our invention.

Figure 2 is a bottom plan view of the pipe wrench shown in Figure 1.

Figure 3 is a view thereof in longitudinal vertical section,

Figure 4 is a view in transverse section on line 4-4 of Figure 1,

Figure 5 is a similar view on line 5-5 of Figure 1,

Referring to the drawings wherein for the sake of illustration is shown the preferred embodiment of the invention, numeral 10 designates generally a hollow shank which is hollow in that it is provided with a longitudinal bore. A fixed jaw 12 is arranged at one end of the hollow shank and preferably is provided with a removable and serrated jaw-face 13.

An operating rod designated generally at 15 is rotatably journaled in the bore of the hollow shank and it has a portion adjacent the fixed jaw 12 formed to constitute an operating screw designated at 16. The operating rod 15 is also provided with a

helical groove 17, the helical groove being provided in a portion of the operating rod which is disposed in the end of the shank that is remote from the fixed jaw. A longitudinally extending slot 18 is formed in its shank adjacent the helical groove 17 and an operating sleeve 19 is slidably mounted on its shank and has secured thereto a pin 20 which extends through the slot 18 and which co-acts with the helical groove 17. In this manner when the operating or traveling sleeve 19 is moved longitudinally the operating rod will be rotated.

A carrier or frame 25 is mounted on the shank and includes side plates 26 which snugly engage the side faces of the shank and end plates 27 and 28. The end plate 28 being curved corresponding to the face of the shank with which it is engaged as clearly shown in Figure 4. A nut designated generally at 30 is fitted in the frame 25 and is carried thereby, the nut operating in a slot 31 extending longitudinally in the shank 10 and along the operating screw 16, the threads of the nut being operatively engaged with the screw 16 as clearly shown in Figure 3. The nut 30 includes laterally extending guide arms 32 and outwardly extending attaching arms 33 integral with the guide arms (see Figure 4). The guide arms 32 slidably engage the portions of the shank adjacent the slot 31 and the attaching arms 33 snugly fit against the side plates 26 of the frame or the carrier 25.

A movable jaw 35 is provided and preferably is equipped with a removable jaw-face 36 having serrations as shown in the drawing. The shank 37 of the movable jaw 35 is pivotally connected to the carrier 25 by means of a pivot pin 38. As shown in Figure 4 the pivot pin 38 has threaded engagement as at 38a with one of the side plates 26 and this pivot pin passes through the attaching arms 33 of the nut as well as through the pivoted shank and in this manner it constitutes common means for pivotally connecting the movable jaw to the frame or carrier and for securing the nut in position. The shank 37 of the pivoted jaw is provided at the end thereof remote from the jaw with a socket 37a, which receives one end of a coil spring 40, the other end of the coil spring projecting from the socket and engaging the nut 30. The coil spring is tensioned to urge the pivoted jaw in one direction so that it will be disposed to

enter into gripping engagement with the work.

In operation the jaws of the wrench may be equally adjusted by manipulating the travelling or operating sleeve 19. Movement of the operating sleeve imparts movement to the operating rod through the pin and helical groove and such movement of the operating rod is imparted to the carrier through the operating screw and the nut. As the movable jaw is supported upon and connected to the carrier, it is constrained to partake of the movement thereof and consequently is adjusted toward and away from the fixed jaw. The spring 40 engages the pivoted jaw to maintain it in proper position with respect to the fixed jaw so that these jaws may immediately come into powerful and gripping engagement with the pipe or work.

What we claim is:

1. In a pipe wrench of the character described, a hollow shank, a fixed jaw arranged at one end of said shank, an operating rod journaled within said shank and having a portion formed to constitute an operating screw and having a helical groove, said hollow shank having a longitudinal slot adjacent the operating screw and a second longitudinal slot adjacent the helical groove, a travelling sleeve slidably mounted on the hollow shank and having a pin extending through the adjacent slot and cooperating with the helical groove, a carrier slidably mounted on the shank and including side plates and end plates, said side plates and one of said end plates having sliding engagement with the shank, a nut fitting in said frame and extending through the adjacent slot and having threads engageable with the operating screw, said nut having laterally extending guide arms engaging the shank and outwardly extending attaching arms engaging the side plates of the carrier, a movable jaw having

a shank received between the side plates of the carrier, a pivot pin for pivotally connecting the shank of the movable jaw to the carrier, said pivot pin also extending through the attaching arms of the nut for securing it in position on the carrier, said shank having a socket formed therein adjacent one end, and a coiled spring having one end received in said socket and having its other end engageable with the nut whereby said pivoted jaw is urged into operative position.

2. In a pipe wrench of the character described, a hollow shank, a fixed jaw arranged at one end of said shank, an operating rod journaled within said shank and having a portion formed to constitute an operating screw and having a helical groove, said hollow shank having a longitudinal slot adjacent the operating screw and a second longitudinal slot adjacent the helical groove, a travelling sleeve slidably mounted on the hollow shank and having a pin extending through the adjacent slot and cooperating with the helical groove, a carrier slidably mounted on the shank and including side plates and end plates, said side plates and one of said end plates having sliding engagement with the shank, a nut fitting in said frame and extending through the adjacent slot and having threads engageable with the operating screw, said nut having laterally extending guide arms engaging the shank and outwardly extending attaching arms engaging the side plates of the carrier, a movable jaw having a shank received between the side plates of the carrier, a pivot pin for pivotally connecting the shank of the movable jaw to the carrier, said pivot pin also extending through the attaching arms of the nut for securing it in position on the carrier.

EDWIN J. EVANS.
GEORGE E. HEMPHILL.
